UNITED STATES PATENT OFFICE.

TIMOTHY R. BARRETT, OF BORDENTOWN, NEW JERSEY.

ILLUSION APPARATUS FOR THEATRICAL AND AMUSEMENT PURPOSES.

1,110,665.

Specification of Letters Patent. Patented Sept. 15, 1914.

Application filed March 30, 1911. Serial No. 617,978.

To all whom it may concern:

Be it known that I, TIMOTHY R. BARRETT, a citizen of the United States, residing in the city of Bordentown, county of Burlington, and State of New Jersey, have invented a certain new and useful Illusion Apparatus for Theatrical and Amusement Purposes, of which the following is a specification.

This invention is an illusion apparatus for theatrical and amusement purposes, the object in view being to convey the impression to an audience that a person apparently in pursuit of a vehicle will fail in an effort to overhaul or catch up with said vehicle.

The invention embodies a representation, of a suitable vehicle, such as a car, an appliance whereon a performer, such as a person, may run, said appliance being herein-after referred to as a treadmill, means whereby a relative movement between the vehicle and the treadmill may be secured at will, a background for the setting constituted by the vehicle and the treadmill, and a foreground for the setting, said background and the foreground being associated with means for securing novel scenic effects.

More specifically stated, the invention is embodied in a treadmill adapted to be moved toward the vehicle, or away from the vehicle, according as it may be desired to give the impression that the performer is gaining upon the vehicle or losing ground in his effort to catch up with the vehicle. Furthermore, the vehicle is mounted so that it is capable of movement relative to the treadmill, and, also, to enable said vehicle to be run off a stage.

The background is embodied in the form of a drop screen composed of a material which is rendered so translucent under the rays of light from a picture projecting apparatus that the image projected in said screen can be seen from the opposite side. Said apparatus is of the kind employing a lens, a source of light, and a rotary slide carrier provided with a series of views exposed in rapid succession so as to give moving pictures involving persistence of vision, whereby there is secured the optical effect of a relative movement between the background and the stage setting, the latter being comprised by the vehicle, the treadmill, and the performer or performers.

The foreground obtains novel scenic effects of rain, snow, etc., by the employment of a substantially invisible drop screen com-

posed of a wide or open mesh fabric against which pictures, representative of rain or snow, are projected by a picture projecting machine, embodying a rotary slide carrier provided with a series of like views exposed in rapid succession so as to give moving pictures involving persistence of vision, said picture projecting machine being independent of the picture projecting machine employed in conjunction with the background screen.

Other features of the invention, and the advantages thereof, will appear in the course of the annexed detailed description.

In the accompanying drawings, I have illustrated one practical embodiment of the invention, but the construction shown therein is to be understood as illustrative, only, and not as defining the limits of the invention, except as defined by the annexed claims.

Figure 1 is a view in front elevation of a stage whereon a theatrical performance is to be carried on by the aid of the appliances of this invention. Fig. 2 is a view at right angles to Fig. 1 illustrating the appliances of this invention in operative position upon a stage.

A designates the floor line of the stage, platform, or other structure, upon which the apparatus of this invention is intended to be installed, for the purpose of giving a theatrical or entertaining performance.

B designates a portion of a vehicle, or simulated vehicle, the same being provided with wheels b, whereby the apparatus is rendered movable and portable upon the stage. As shown, the vehicle represents the end portion of a railway car having a platform b' and steps b'', but the particular form of the vehicle may be modified and changed according to the theatrical act which is to be given. In some instances, I may employ an automobile as the vehicle, but as there are a large variety of automobiles, and as other forms of vehicles may be substituted, I have not considered it necessary or expedient to illustrate the forms of vehicles which may be used in the performance. The vehicle is intended to occupy, or be positioned at, the end portion of the stage, and said vehicle is intended to be moved onto and off the stage, and during the performance of the act the vehicle may or may not be moved with respect to the treadmill presently described, such

movement of the vehicle being effected by stage hands in the flies, or by suitable mechanism provided for the purpose.

The portable treadmill C is positioned on the stage adjacent to the vehicle, said treadmill being movable relative to said vehicle. The particular form of treadmill which I prefer to employ is disclosed in an application filed by me on February twenty-eighth, one thousand nine hundred and eleven, Serial No. 611,495. Said treadmill embodies a frame c and an endless path c', the latter being supported by suitable means within frame c so as to run easily therein when a performer is engaged in giving the act. As shown in Fig. 1, the treadmill is provided, also, with suitable carrying wheels d, adapted to rest upon the floor of the stage or platform, whereby the treadmill may be easily transported to and from the stage, and it is rendered capable of moving upon the stage with relation to the vehicle. One embodiment of means for operating the treadmill at will, consists of a cable E, such as the endless cable shown in Fig. 1. The cable is shown as being attached at its respective ends to the ends of the treadmill frame c. The cable extends around the pulleys are positioned at the respective sides to and around another pulley e', and thence attached to the treadmill frame. The pulleys are positioned at the respective sides of the stage, and the operating cable is practically concealed from the view of the audience. One of the pulleys, as e, may be power operated. The cable, or equivalent device, provides means for imparting movement at will to the treadmill, whereby said treadmill may be caused to approach closer to the car or vehicle, or it may be made to recede therefrom.

A background screen F is positioned at the rear of the stage setting, said background screen being in the form of a drop curtain, composed of a material which will be rendered so translucent by the rays of light from a picture projecting apparatus G that the image projected thereon can be seen from the opposite side of the screen. The screen may be composed of a fabric of any desired color, preferably white, and this fabric is not painted or decorated like ordinary background curtains employed as theatrical scenery. The picture projecting apparatus G is positioned in the rear of the screen so as to be concealed from the view of the audience, and during the performance said apparatus G is operated to throw against the screen a continuous view which gives a continuously moving scene. The form of projecting apparatus which I prefer to employ consists, generally, of a light-tight casing g adapted to inclose a source of light, such as an electric arc light, a lens tube g', and a rotary slide carrier adapted

to be operated by clock work, or other form of motor mechanism designed to impart rotary motion to said slide carrier, said slide carrier being provided with pictures of one continuous view which gives a continuously moving scene.

For the purpose of securing rain, snow and other effects, I employ a foreground curtain H and a picture projecting apparatus I, adapted to coöperate with said foreground curtain. The foreground curtain is composed of a wide or open mesh fabric, so as to be substantially invisible to the eye of a person in the audience, but the fabric of this foreground curtain is of such a nature that the pictures projected from apparatus I will be depicted upon the curtain, so as to give the effect to the audience of rain, snow or other scenic effects. The foreground curtain is suspended or supported between the audience and the stage setting, as shown in Fig. 2. The apparatus I is similar in construction to the apparatus G heretofore described, and it is operated in a similar way to throw against screen H a series of like views exposed in rapid succession so as to give moving pictures involving a persistence of vision. Said apparatus I may be located at any suitable place in front of the stage, usually in a balcony of the theater in which the performance is given.

Prior to giving the performance the vehicle and the treadmill are positioned at one end portion and in the central portion, respectively, of the stage, the background screen F is placed in position at the rear of the stage setting, and the foreground screen H is positioned in front of the stage setting, screen H being between the audience and the stage setting. The projecting apparatus G is at the rear of the stage, whereas apparatus I is preferably at an elevated point in the body of the theater. When the stage curtain is raised, the apparatus G is operated to throw a strong light against screen F, and also, the rotary slide carrier is operated so that a series of pictures will be thrown in rapid succession against screen F. The vehicle is positioned so that it will apparently travel from left to right, but the pictures thrown by apparatus G against screen F will travel apparently in the opposite direction, or from right to left, in order to secure the desired illusion as to the movement of the vehicle which, as a matter of fact, will be at rest, except when said vehicle is moved with relation to the treadmill. The central theme of the performance is the actor running upon the treadmill in pursuit of the vehicle, and the illusion is increased by moving the treadmill bodily with relation to the vehicle. The treadmill, while the actor is performing thereon, may be drawn at will toward the vehicle so as to give the effect that the pursuer is gaining upon the vehicle, and at

other times, the treadmill is drawn away from the vehicle while the actor is performing thereon, thus giving the effect that the pursuer is failing in his efforts to overtake the vehicle. The dramatic effect may be still further increased by an actress at the rear platform of the car or vehicle, all as shown in Fig. 1. To further enhance the theatrical effect, the apparatus I is operated to throw in rapid succession a series of pictures against the substantially invisible foreground curtain, said pictures giving a rain, snow or other effect. The treadmill may be substantially concealed from view by suitably painting the lower part of curtain H, or other foregrounds may be employed to conceal the treadmill.

Having thus fully described the invention, what I claim as new, and desire to secure by Letters Patent is:—

1. In an illusion apparatus, the combination with a foreground and a background, of a treadmill positioned intermediate said foreground and background, and a movable simulated vehicle or car provided with means for the accommodation of a performer, said simulated vehicle or car being provided with carrying wheels adapted to run upon the stage and said car or vehicle being movable at will toward and from the treadmill.
2. In an illusion apparatus, the combination with a foreground and a background, of a wheeled vehicle or car provided with means for the accommodation of a performer, said vehicle or car being positioned intermediate the foreground and the background and being movable at will across the stage, a wheeled treadmill adjacent to said car or vehicle, and means operatively connected with said treadmill and operable at will for moving said treadmill toward and from the car or vehicle.
3. In an illusion apparatus, a background, a foreground, a wheeled vehicle positioned intermediate the background and the foreground, a treadmill adjacent to the wheeled vehicle, and means for bodily moving said treadmill relative to the wheeled vehicle, said wheeled vehicle being movable at will relative to the treadmill.
4. In an illusion apparatus, a stage setting embodying a simulated vehicle and a treadmill movable relative to each other, a background screen at the rear of the stage setting, means for projecting a series of pictures in rapid succession against said background screen, a substantially invisible screen positioned in front of the stage setting, through which screen the stage setting is visible to the audience, and separate means for projecting a series of pictures in rapid succession against the substantially invisible screen.
5. In an illusion apparatus, a translucent
- background screen and means for projecting pictures in rapid succession against it, a substantially invisible foreground screen composed of open mesh fabric, means for projecting a series of like views in rapid succession against the foreground screen, and a stage setting positioned intermediate the background screen and the foreground screen, said stage setting being exposed to the view of an audience through the foreground screen.
6. In an illusion apparatus, a stage setting including a vehicle and a treadmill adapted to be moved relatively one to the other, a background screen, and picture projecting mechanism adapted to throw against the screen a series of pictures depicting scenes moving in an opposite direction to that in which the vehicle is apparently moving.
7. In an illusion apparatus, the combination of a background screen composed of a substantially translucent material, means for projecting a succession of pictures against it, a substantially invisible foreground screen composed of an open mesh fabric, means for projecting against the foreground screen a succession of pictures, and a stage setting positioned intermediate the foreground screen and the background screen, said stage setting embodying means whereby a theatrical performance may be conducted intermediate the aforesaid screens.
8. In an illusion apparatus, a stage setting, embodying a treadmill and a simulated vehicle, a substantially invisible foreground screen positioned in front of the stage setting, and means for projecting a succession of pictures against said screen.
9. In an illusion apparatus, a stage setting, a substantially invisible foreground screen positioned in front of the stage setting, and a picture projecting apparatus positioned in front of the screen and operating to project a succession of pictures against the same, said stage setting being exposed to the view of an audience through said foreground screen.
10. In an illusion apparatus, the combination of a background screen composed of a substantially translucent material, means for projecting a succession of pictures against it, a substantially invisible foreground screen composed of an open mesh fabric, means for projecting against the foreground screen a succession of pictures, and a simulated vehicle and a treadmill both positioned intermediate the foreground screen and the background screen for the purpose of enabling a theatrical production to be performed intermediate said screens.
11. In an illusion apparatus, a stage setting embodying a simulated vehicle and a treadmill, means for securing at will a relative movement between the vehicle and the

treadmill, a background screen, means for throwing a succession of pictures against said screen, a foreground screen, and an independent means for throwing a succession 5 of pictures against the foreground screen.

12. In an illusion apparatus, a stage setting embodying a simulated vehicle and a treadmill, means for securing at will a relative movement between the vehicle and the treadmill, a background screen, a picture projecting apparatus at the rear of the background screen for throwing a succession of 10 pictures against it, a substantially invisible

foreground screen in front of the stage setting, and a picture projecting apparatus 15 positioned in front of the foreground screen and adapted to throw a succession of pictures against it.

In testimony whereof I have signed my name to this specification in the presence of 20 two subscribing witnesses.
